(57) **CLAIM**

The ornamental designs for a drifting kart, as shown and described.

DESCRIPTION

FIG. 1 is a top, rear, and right side perspective view of a drifting kart which embodies my design;

FIG. 2 is a top, front, and left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof.

FIG. 8 is a top, rear, and right side perspective view of a second embodiment of a drifting kart which embodies my design;

FIG. 9 is a top, front, and left side perspective view thereof;

FIG. 10 is a front view thereof;

FIG. 11 is a rear view thereof;

FIG. 12 is a right side view thereof;

FIG. 13 is a left side view thereof; and,

FIG. 14 is a top view thereof.

Broken lines are used to illustrate features of the drifting kart which form no part of the claimed design.

1 Claim, 14 Drawing Sheets
